POWER TAKE-OFF

John R. Betts, Kearney, Nebr.

Application May 17, 1937, Serial No. 142,969.

4 Claims. (Cl. 290—55)

My invention relates to power take-offs, its primary object being the provision of a power take-off which may be applied to the windmills now in use and operated without disturbing or in any way interfering with the normal operation of the windmill.

Another of my objects is the provision of a power take-off which may be applied to a windmill without the necessity of drilling holes or otherwise fitting the power take-off to the windmill while on the job.

Another of my objects is the provision of a power take-off which may be adapted with the minimum of effort to any commercial windmill at present in use.

A very important object of the invention is the provision of an attachment including a generator which may be applied to a windmill to be used for generating electrical current without disturbing the pumping operation of the windmill and so arranged that either the pump alone or the generator alone or the pump and generator together may be operated.

Having in view these objects and others which will be pointed out in the following description, I will now refer to the drawing, in which

Figure 1 is a view partly in vertical section and partly in elevation of a windmill motor with my take-off connected thereto, a portion of the oil reservoir being broken away to disclose the windmill gearing.

Figure 2 is a similar view showing the parts as seen from a position at one quadrant from the position in which Figure 1 is viewed.

Figure 3 is a view in perspective showing the exterior portions of the helmet with my power take-off applied thereto.

Almost without exception all windmills at present in use on farms have certain features in common. Among these are the wind wheel shaft 10 having a gear 11 in mesh with a speed reducing gear 12 on the shaft 13. Included also is a pitman 14 eccentrically secured to the gear 12, the upper extremity of the pitman being pivotally connected with the pump rod 15 which extends downwardly through the mast 16. The pump rod 15 is maintained during movement in vertical position by means of a guide which in the form shown in my drawing consists of a vertical yoke 17 for guiding the movements of the roller 18 which is journaled on the pivotal connection between the pitman 14 and the pump rod 15.

The lubrication system is usually of the splash type, the reservoir 19 serving for the storage of the lubricant. A helmet 20 has two functions:

to prevent the loss of lubricant through splashing and to prevent the entrance of water and grit into the lubricant and into the gearing. The helmet 20 seats against a peripheral flange of the lubricant reservoir and is secured in place by means of a bolt and nut connection 21, the bolt projecting upwardly from a fixed part of the windmill such as the yoke 17 and passing through an aperture in the top of the helmet, the nut being drawn down against the upper surface of the wall of the helmet.

Thus far the construction is common to nearly all windmills and is varied in only minor details such as the dimensions. In most cases the gears and pitmans are duplicated in symmetrical relation on the two sides of the pump rod 15 as shown in Figure 2. My problem has been to devise means for taking the power off any of the present windmills by utilizing to the greatest possible extent the structures already present in the windmill. This I accomplished merely by the use of accessories on the windmill, it being only necessary that the windmill have a helmet and a driven gear similar to the gear 12.

The helmet which I employ must be similar to those of the windmill to which my power take-off is to be applied. These helmets may be best obtained from the windmill manufacturers. The helmet should be apertured and provided with bearings 22 for a shaft 23. The shaft 23 carries a gear 24 meshing with the gear 12 of the windmill. It is necessary that the shaft 23 with its gear 24 conform to the position of the parts of the gearing in the windmill to which my power take-off is to be applied. The shaft 23 carries at one of its extremities a pulley wheel 25. At 26 is a generator having a shaft 27 which is parallel to the shaft 23. The shaft 27 has a pulley wheel which is belted to the pulley wheel 25. The generator is firmly secured to the helmet by means of straps 28 which may be welded or otherwise secured to the helmet. In order to maintain operative tension on the belt 29 I provide an idler 30 resting yieldably against the upper run of the belt 29 but any of the well-known belt tensioning devices may be employed for maintaining the proper tension in the belt 29.

The great advantage of the present structure is that no changes whatever need be made in the windmill itself and that the device may be easily applied to the windmill or removed therefrom. Since the generator is driven directly from the windmill motor and not from the wind wheel, no side movement of the gears is encountered such as would cause fluctuation in the driving of the

generator. The helmet with my attachments may be secured to the windmill for approval since all that is necessary is to remove the helmet of the windmill and to secure the helmet 20 with my attachment in its place. The change can be made in a few minutes' time so that the device is ready for immediate use. If it is approved and the sale is made, the old helmet may be fitted with a generator as shown so that it will be available for use on a similar windmill. If the sale is not made the device may be removed and the old helmet replaced without in any way interfering with the normal operation of the windmill.

My power take-off with the generator is designed to in large measure solve the problems of rural electrification. Nearly all farms are now equipped with windmills which at present are being used exclusively for pumping water. Such windmills as a rule are used only during a portion of the time while the wind is blowing so that the equipment stands idle at other times. Even when the windmill is pumping water the power available is often greatly in excess of that required in normal pumping operations. The devices are assembled at central points, the helmets being the standard helmets for the windmills of various kinds. The bearings 22 are applied in the proper positions to the opposite walls of the helmet and the shaft 23 with the gear or gears 24 is journaled in these bearings. The generator 26 is then secured by means of straps 28 to the outer surface of the helmet. All of this requires the minimum of labor when the work is done in a shop equipped with the necessary but minimum number of tools. On leaving the shop the helmet with its attachments is ready for almost instant installation on the windmill since it necessitates only the removal of the windmill helmet and its replacement by my helmet with the attachments. This is an exceedingly simple operation since it necessitates only the removal of the nut 21 from the old helmet and the replacement of the nut after my helmet has been installed. While the entire labor cost has been reduced to a minimum the labor cost on the job is brought down to a very insignificant figure.

My power take-off for the generation of electrical current should be of particular appeal to tenant farmers. On tenant farms the landlord is seldom willing to stand the cost of the connection with the power line and of the cost of wiring the buildings for a current of high voltage. On the other hand, the tenant is unable to meet this cost especially in the face of the fact that the installation then belongs to the landlord. As before stated, the cost of my installation is relatively low because of the ease and low labor cost of making the installation on a particular windmill. If the tenant then finds that he must move at the end of the year to a new location, he simply removes and takes with him the helmet having the generator secured thereto. In case he finds a windmill of different make on the farm to which he moves, the shop may be stocked with the helmets for windmills of different makes so that the change may be made at very low cost in the shop.

The equipment may include a storage battery for the lighter operations such as that required by the sewing machine or cream separator or for use in the lighting system while the generator is not being operated. The generator may also

be employed for charging automobile batteries or radio batteries.

Having thus described my invention in such full, clear, and exact terms that its construction and operation will be readily understood by others skilled in the art to which it pertains, what I claim as new and desire to secure by Letters Patent of the United States is:

1. An attachment for a windmill having gearing driven by a wind wheel and means for seating a helmet for covering the windmill gearing, said attachment including a helmet, aligned bearings in a pair of opposite side walls of said helmet, a shaft journaled in said bearings, a gear secured to said shaft to rotate therewith, said gear being so positioned as to be in mesh with a gear of the windmill motor when said helmet is seated, a power take-off secured to an outer side of said helmet, said power take-off having a shaft in parallel relation with said first named shaft, and means for driving said power take-off shaft from said first-named shaft.

2. A windmill including a lubricant reservoir, a helmet above said reservoir, a wind wheel motor enclosed by said lubricant reservoir and said helmet, a shaft for driving said motor, a wind wheel outside said reservoir for driving said shaft, said motor including a gear on said shaft, a second shaft journaled in opposite walls of said helmet, a gear on said second shaft and meshing with said first-named shaft, said second shaft projecting outside said helmet on one side thereof, a pulley wheel at the outer extremity of said shaft, a generator secured to said helmet on the outer side thereof, a pulley wheel on the shaft of said generator, and a belt connecting said two pulley wheels.

3. An attachment for a windmill having a lubricant reservoir and flanges at the upper edge thereof for seating a helmet and having also a wind wheel and a shaft driven by the wind wheel and journaled in the side walls of the reservoir, the windmill motor including a gear on the shaft of the wind wheel and a speed reduction gear driven by the gear on the wind wheel shaft, said attachment including a helmet adapted to seat on the edge portion of the lubricant reservoir of the windmill and adapted to be secured thereto, a generator secured to the outer side of a wall of said helmet, said generator having a shaft, a second shaft journaled in opposite walls of said helmet in parallelism with said generator shaft, a gear on said second shaft and positioned to be in mesh with the speed reduction gear of the windmill when said helmet is secured to the oil reservoir of the windmill, aligned pulley wheels on said two shafts, and a belt connection between said two pulley wheels.

4. An attachment for windmills of the kind having gearing driven by a wind wheel and a helmet for covering the windmill gearing, said attachment including a shaft having a gear adapted to mesh with a gear of the windmill gearing, a generator adapted to be secured to the windmill helmet on the outer side thereof, said generator including a shaft in parallel relation with the first said shaft of said attachment, and a connection between said two shafts whereby the first said shaft will drive said generator.

JOHN R. BETTS.
